DESIGN FOR A DRESS

Natalie Renke, New York, N. Y.

Application July 31, 1941, Serial No. 102,586

Term of patent 3½ years

To all whom it may concern:

Be it known that I, Natalie Renke, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design, and

Fig. 2 is the rear view thereof.

My design comprises a wool shirt waist dress of the configuration disclosed having a wide inserted band of velvet in the blouse with set in wool pockets on the front and an alternate arrangement of velvet and wool bands in the skirt, all as shown.

I claim:

The ornamental design for a dress, substantially as shown and described.

NATALIE RENKE.
